UNITED STATES PATENT OFFICE.

CARL HOFFMAN, OF ALLENTOWN, PENNSYLVANIA.

DOOR LOCK.

Application filed October 9, 1922. Serial No. 593,283.

To all whom it may concern:

Be it known that I, CARL HOFFMAN, a citizen of the United States, residing at Allentown, in the county of Lehigh, State of Pennsylvania, have invented certain new and useful Improvements in Door Locks; and I do hereby declare the following to be a full, clear, and exact description of the invention, such as will enable others skilled in the art to which it appertains to make and use the same.

My invention relates to door locks and more particularly to such as combine in a single element the latch by which the door may be readily opened upon manipulation of a knob and the dead bolt which requires a key to operate it, and the object of my invention is to provide a simple and efficient device of this character composed of but few parts so assembled as to insure ease and certainty in operation and security in both its use as a latch and a lock.

In the drawings, Figure 1 is a view in side elevation with the cover plate of the lock case removed and the door and its casing shown in section, the parts being illustrated in latching position. Figure 2 is a vertical sectional view on line 2—2, Figure 1. Figure 3 is a cross sectional view on line 3—3, Figure 1. Figure 4 is a vertical sectional view on line 4—4, Figure 2. Figure 5 is a detail perspective view of the latch and its supporting arm. Figure 6 is a detail perspective view showing the two spindles with their knobs and the latch operating lever. Figure 7 is a view similar to Figure 1, showing the latch held in retracted position. Figure 8 is a view in side elevation with the cover plate broken away to show the latch in dead lock position. Figure 9 is a detail perspective view of a portion of the lock case. Figure 10 is an enlarged view and Figure 11 a perspective view of the stop for holding the latch retracted. Figure 12 is a perspective view of the means for holding the latch dead locked.

The lock case is of the usual type having side plate 2 which fits flush with the edge of the door; bed plate 3 with posts and guides; a cover plate 4, these plates having the necessary openings for the different parts of the lock. 5 designates the latch supported at one end of a right angular arm or lever 6 which has a downwardly extending lug 7. A spring 8 bears against the latch 5 to urge it into latching position and from which po-

sition it may be withdrawn by a lever 9 operated by outer or inner knobs at the ends of spindles 10, 11, the squared end of the latter fitting in the squared bore of the hub 12 of the lever. This squared end of the spindle 11 is mortised as at 13 to receive the tenon 14 of the spindle 10 and it also has a lateral projection 15.

At 20 I have shown the latch bolt. This is provided with a slot 21 to receive a projection 22 of the bed plate which with a bar 23 of the latter and the pin 24 working in a second slot 25 of the latch bolt forms a guide for such latch bolt. Talons 26—27 and 28—28^a form the means by which the bolt is moved by a key. At the end of the latch bolt next adjacent the latch is a stud 29 which is designed, in one position of the parts (see Figure 8), to act as a stop, contacting with the back of the latch 5, to prevent retraction of the same and in another position (see Figure 1) to retract the latch upon manipulation of the bolt by a key, the stud in this last named position acting against the downwardly extending lug 7 of the latch. A lateral projection 30 is provided on the latch bolt by which it may be locked in its different positions, cut outs 31 of a spring controlled tumbler 32 registering with such projection for that purpose, the tumbler being pivoted on the pin 24 so that it may be moved from engagement with the latch bolt by a key preparatory to movement of the bolt by such key.

For the purpose of holding the latch either retracted or set as a dead bolt I provide a stop button 40 the arm 41 of which may be turned to engage the supporting arm of the latch, as shown in Figure 7, to hold it retracted or, when the latch is protracted to hold it against movement, the arm 41 being so shaped, as indicated in Figure 11 as to engage the end of the latch arm 6, as shown in Figure 10. Fingers 42 are provided on the shank of this button to engage a short post 43 and limit the turning movement of the stop.

As heretofore explained, the spindles 10 and 11 are tenoned and mortised so that operation of the lever arm by the knob 50 on the outside of the door can only be accomplished when its tenon is fitted in the mortise of the spindle 11. In Figure 2 I have shown the parts in operable position. If it be desired to prevent operation of the latch from the outside by the door knob, when the

latch bolt is not set in locking position, the inner knob 51 is turned so that the lateral projection 15 may pass under the lip 52 on the inside of the door plate which will allow 5 the spindle 10 to be drawn inwardly and out of engagement with its complementary spindle 9. The lip, upon appropriate turning of the knob, then acts as a stop against inward movement of the spindle 11. So disengaged, 10 the outer spindle 10 will merely swing around without in any way effecting movement of the lever. So that the knob 50 may always be in a position where its tenon will be ready for engagement with the spindle 11 I provide a weight 53 on the knob which will cause the knob to swing so that the tenon will normally stand vertically.

In the position of the parts shown in Figure 1, the latch may be manipulated by the 20 spindle 11 from inside the door and by the spindle 10 from outside if the two spindles are in coupled position. If not coupled the latch may only be operated from the outside by a key acting first to disengage the tumbler 32 and then against the talon 27 of the latch bolt which will, through engagement of the stud 29 with the lug 7 of the latch force the latter against the tension of its spring. To dead lock the latch bolt it is 30 necessary to use a key from either inside or outside and once set in locking position this latch bolt cannot be moved by any manipulation of the lever 9, a key being necessary to first remove the latch bolt from its locking 35 position. The parts are shown in their locked position in Figure 8.

I claim as my invention:

1. A latch and lock mechanism for doors including a case, a movable latch, actuating means for said latch, a single movable key actuated member for locking said latch against retraction, being directly engageable with said latch, and said key actuated member being cooperable with said latch for actuating the same.

2. A latch and lock mechanism for doors including a case, a movable latch, actuating means for said latch, a movable key actuated member for locking said latch against retraction, means controlled by the movement of said member and cooperating with said latch for actuating the same, and means for rendering both of said latch actuating means ineffective.

3. A latch and lock mechanism for doors including a case, a spring actuated latch, a lever for retracting said latch, a pair of spindles for operating said lever, means permitting disengagement of one of said spindles to prevent manipulation of the lever by rotation of the spindle, and means engageable with said lever for locking the same against movement by either spindle.

4. A latch and lock mechanism for doors, including a case, a spring actuated latch, a

lever for retracting said latch, a pair of spindles for operating said lever, means permitting disengagement of one of said spindles to prevent manipulation of the lever by rotation of the spindle, and key actuated means movable in one direction for locking said lever against actuation by either spindle and movable in another direction for moving said latch and lever therewith.

5. A latch and lock mechanism for doors including a case, a spring actuated latch, a lever for retracting said latch, a pair of spindles for operating said lever, means permitting disengagement of one of said spindles to prevent manipulation of the lever by rotation of the spindle, means cooperating with said latch for locking said lever against movement by either spindle, and means controlled by the movement of said latch-locking means for moving said latch and lever.

6. A latch and lock mechanism for doors including a case, a spring actuated latch, a lever for retracting said latch, a pair of spindles for operating said lever, means permitting disengagement of one of said spindles to prevent manipulation of the lever by rotation of the spindle, key actuated means cooperating with said latch for locking said lever against movement by either spindle, and means controlled by the movement of said latch-locking means for moving said latch and lever.

7. A latch and lock mechanism for doors including a case, a spring actuated latch, a lever for retracting said latch, knob operated spindles for moving said lever, means for retracting said latch independently of said spindles, and means engageable with said lever for locking said latch against retraction by said lever or said last named means.

8. A latch and lock mechanism for doors including a case, a spring actuated latch having a right angular portion, a lever designed to engage said right angular portion to retract said latch, means for operating said lever, a movable member for engaging and holding said latch against movement by said lever, a spring actuated tumbler for locking said member in holding position, and means associated with said member and latch retracting the latter upon movement of said member in one direction.

9. A latch and lock mechanism for doors including a case, a spring actuated latch having a right angular portion, a lever designed to engage said right angular portion to retract said latch, means for operating said lever, and a key-actuated tumbler-controlled member having means for engaging said latch, said member being movable into one position to lock said latch against movement by said lever and into another position to retract said latch by key manipulation.

10. A latch and lock mechanism for doors including a case, a spring actuated latch having a right angular portion, a lever designed to engage said right angular portion to retract said latch, means for operating said lever, a key-actuated tumbler-controlled member having a stud for engaging said latch, said member being movable into one position to lock said latch against movement 5 by said lever and into another position to retract said latch by key manipulation, and means engaging said right angular portion of said latch to lock the latter against movement by either said lever or key actuated 10 member.
11. A latch and lock mechanism for doors including a case, a spring actuated latch, a lever for retracting said latch, a spindle connected with said lever for operating it from 15 one side of a door, a second spindle with which said first named spindle is designed to engage to operate said lever from the opposite side of a door, a stop acting on said first mentioned spindle to prevent 20 coupling with said second spindle, and means engageable with said lever for locking the same against movement by either spindle.
12. A latch and lock mechanism for doors 25 including a case, a spring actuated latch, a lever for retracting said latch, a spindle connected with said lever for operating it
- from one side of a door, a second spindle with which said first named spindle is designed to engage to operate said lever from the opposite side of a door, a stop acting on said first mentioned spindle to prevent 30 coupling with said second spindle, key actuated tumbler-controlled means for engaging said latch, said means being movable into one position to lock said latch against movement by either spindle and into another position to retract said latch by key manipulation, and a rotary element cooperating 35 with said latch to prevent operation by said spindles or said key actuated means.
13. In a latch and lock mechanism for doors, the combination of a rotatable spindle including separable interlocking sections, knobs on said spindles and a weight on one 40 of said spindles for maintaining it in a predetermined position to engage the end of the other spindle.
14. In a latch and lock mechanism for doors, the combination of a rotatable spindle including separable interlocking sections, knobs on said spindles and means acting upon one of said spindles normally tending 45 to maintain it in a predetermined position to engage the end of the other spindle.

In testimony whereof I have signed this specification.

CARL HOFFMAN.
